UNITED STATES PATENT OFFICE.

ANTHONY ROTH, JR., OF NEW BRUNSWICK, NEW JERSEY.

SCREEN.

1,190,676.

Specification of Letters Patent.

Patented July 11, 1916.

Application filed August 19, 1915. Serial No. 46,296.

To all whom it may concern:

Be it known that I, ANTHONY ROTH, Jr., a citizen of the United States, residing at New Brunswick, in the county of Middlesex

5 and State of New Jersey, have invented a new and useful Screen, of which the following is a specification.

The device forming the subject matter of this application is adapted to be employed in connection with a window frame and with a horizontally extensible screen, the construction being such that the horizontally extensible screen may be mounted for vertical sliding movement on the frame.

10 15 The invention aims to provide novel means for mounting the screen for vertical reciprocating movement, and to provide novel means whereby the screen may be held extended, so that the stiles thereof will engage slidably with tracks which are carried by the window frame.

It is within the province of the disclosure to improve generally and to enhance the utility of devices of that type to which the 20 25 present invention appertains.

With the above and other objects in view which will appear as the description proceeds, the invention resides in the combination and arrangement of parts and in the 30 35 details of construction hereinafter described and claimed, it being understood that changes in the precise embodiment of the invention herein disclosed can be made within the scope of what is claimed, without departing from the spirit of the invention.

In the accompanying drawing:—Figure 1 shows in front elevation, a screen constructed in accordance with the present invention; Fig. 2 is a fragmental vertical section of the screen parts being broken away; Fig. 3 is a fragmental horizontal section taken through one of the stiles of the screen; Fig. 4 is a perspective showing one of the tracks; Fig. 5 is a horizontal sectional view wherein a modified form of track is embodied; Fig. 6 is a fragmental vertical section of the track shown in Fig. 5; Fig. 7 is a perspective showing a modified form of clip whereby relative movement between the 40 45 50 parts of the screen may be prevented; Fig. 8 is a fragmental transverse section showing the clip of Fig. 8 in position. Fig. 9 a perspective showing a slightly modified form of the invention.

55 In the drawings there is shown a hori-

zontally extensible screen of ordinary form, embodying stiles 1, top rails 2 and bottom rails 3, the stiles 1 being provided with grooves 4.

The numeral 5 indicates a portion of a window frame carrying tracks 6 provided with offset feet 7 whereby the tracks may be secured to the frame. The screen is expanded until the tracks 6 are received in the grooves 4, whereupon the screen may be slid vertically.

The top rails 2 of the constituent parts of the screen are gripped by a resilient, U-shaped clip 8, and the bottom rails 3 of the constituent parts of the screen are gripped by a U-shaped, resilient clip 9 embodying a lifting handle 10. The function of the resilient clips 8 and 9 is to prevent the screen from contracting after it has been expanded so that the tracks 6 are received in the grooves 4. It is to be observed that in lifting the screen, an upward pull is exerted on the handle 10, thereby seating the clip 10 more firmly on the bottom rails of the screen.

80 The construction above described is adapted to be employed in connection with a lower screen. In Fig. 5, one of the stiles 11 of a horizontally extensible screen is shown, the stiles 11 having grooves 12. A track 14 is received in each of the grooves 12, the track 14 preferably being fashioned from metal and being U-shaped in cross section. The track 14 is held to the upper portion of the window frame 15 by means of securing elements 16. It is obvious that an upper screen must be prevented from moving downwardly, and with this end in view, resilient tongues 17 are struck outwardly from the tracks 14, the tongues 17 exerting a frictional pressure against the stiles 11 on the upper screen, to hold the same against downward movement.

95 In Figs. 7 and 8, a modified form of the invention is shown, the top rails of the horizontally extensible screen being designated by the reference character 18. The top rails 18 are embraced by a resilient, U-shaped clip 19 embodying an extension 20 pivoted as indicated at 21 to one of the top rails 18. A tongue 22 is struck out of the clip 19 and its extension 20, the tongue 22 terminating in a transverse, outwardly flexed finger piece 23 whereby the tongue 22 may be manipulated. The tongue carries an inwardly pro-

110

jecting stud 24 adapted to be received in a recess 25 in one of the top rails 18.

By means of the stud 24 which is received in the recess 25, the clip 19 is prevented from swinging on its pivot 21 and consequently the clip will remain engaged with the top rails 18 of the window frame, to prevent relative sliding movement therebetween. By means of the finger piece 23, the tongue 22 may be manipulated, so as to disengage the stud 24 from the recess 25, whereupon the clip 19 may be swung on its pivot 21 to detach the clip from the top rails 18, and then expansion or contraction of the screen may be brought about readily.

In this invention there is disclosed a novel means whereby an ordinary horizontally expandable screen may be adapted readily for vertical movement on a window frame.

20 As indicated in Fig. 9, the device may be mounted to slide in a channel 100 having reduced ends 101 provided with openings 102 adapted to receive securing elements whereby the channel may be attached to a window sash.

Having thus described the invention, what is claimed is:—

20 1. In a device of the class described, a frame; tracks carried thereby; a multi-part expandable screen comprising means for engaging the tracks, the parts of the screen including cross rails located side by side; and a removable, resilient, U-shaped clip engaging the cross rails and exerting pressure on the outer faces thereof, to prevent movement between the parts of the screen.

35 2. In a device of the class described, a

frame; tracks carried thereby; an expandable screen comprising parts having means to engage with the tracks; and a resilient, U-shaped clip engaging the lower edges of the said parts of the screen, the clip having a handle constituting, at once, a means for lifting the screen, and a means for seating the clip on the said parts of the screen.

40 3. In a device of the class described, a frame; tracks assembled with the frame, the tracks being arched in cross section and having resilient tongues struck therefrom; an expandable screen comprising parts coacting with the tracks, the tongues coacting with the said parts of the screen to prevent a dropping movement of the screen; and means engaging the said parts of the screen to prevent relative sliding movement therebetween.

45 4. In a device of the class described, a frame; tracks carried thereby; an expandable screen provided with means for engaging the tracks slidably, the screen comprising relatively movable parts; and a resilient, U-shaped clip engaging the said parts of the screen, the clip being pivoted to one of said parts and being provided with a movable locking tongue engaging one of the said parts of the screen.

50 In testimony that I claim the foregoing as my own, I have hereto affixed my signature in the presence of two witnesses.

ANTHONY ROTH, JR.
